UNITED STATES PATENT OFFICE.

GEORGE W. STARR AND WILLIAM D. PAYNTER, OF GRASS VALLEY, CALIFORNIA.

MINING MACHINE.

Application filed July 25, 1921. Serial No. 487,343.

To all whom it may concern:

Be it known that we, GEORGE W. STARR and WILLIAM D. PAYNTER, citizens of the United States, residing at Grass Valley, in 5 the county of Nevada and State of California, have invented certain new and useful Improvements in Mining Machines, of which the following is a specification.

Our invention relates to mining machines, 10 and more particularly to machines for chipping out ore bodies.

The primary object of our invention is to provide a machine for mechanically chipping out a vein of ore without removing any 15 appreciable quantity of the surrounding waste rock. By the use of such a machine, the necessity for blasting is obviated, with appreciable quantity of the surrounding rock and relatively large expense for re- 20 moval of waste and increased timbering, and the cost of working and handling the ore is greatly reduced, not only by the elimination of much hand labor, but also by the fact that the ore removed is clean and prac- 25 tically free from waste rock; as well as being in a more finely divided state than when removed by blasting.

In the use of the machine embodying our invention, a series of substantially horizontal or slightly inclined stope drifts are run 30 into the vein, parallel with each other and at regular and frequent intervals. In actual practice, it is desirable to make these stope drifts about four feet in diameter, 35 and about eight feet apart. After the stope drifts are driven, the eight feet of vein remaining between them is chipped out, care being taken to remove as little of the waste rock as possible. It is for this chipping out 40 of the vein, between adjacent stope drifts, that the machine embodying the present invention is primarily intended; but it is to be distinctly understood that the use of the machine is not limited to this purpose. On 45 the contrary, our machine is capable of use in a variety of situations and for a great number of purposes, and may, in fact, be used for any chipping process to which its construction lends itself.

50 It will be seen from the foregoing explanation that such a machine must have two principal characteristics, viz: it must be capable of operating at right angles to the axis of the stope drift and within a comparatively wide range of elevation and de-

pression; and it must not only be sufficiently compact to operate within the relatively small stope drift, but must be capable of lateral extension sufficient to enable it to penetrate at least to the center of that portion of the vein between two adjacent stopes. 60

The machine embodying our present invention has these two described characteristics; and by reason of its novel construction, is well adapted for working efficiently, even 65 at the limit of its extension. This will be apparent from the following description, when read with reference to the accompanying drawings. It is to be understood, however, that our invention is herein described 70 and illustrated only in its preferred form, and that changes, within the scope of the claims hereto appended, may be made in the form and construction of the machine, without departing in any manner from the 75 essential spirit of the invention.

Broadly speaking, our invention comprises an apparatus for supporting a battery of percussion machines of any desired type, and operated by compressed air or other motive power. Said percussion machines are directed laterally, that is at right angles to the longitudinal axis of the supporting carriage, are operable through wide angles of elevation and depression above 80 and below the horizontal, and are fed into the vein or ore body as the latter is chipped away by the action of their drill bits. Moreover, the entire battery is continuously 85 and automatically reciprocated, both vertically and horizontally, so that the entire working face of the vein is covered by the drills. 90

In order to fully comprehend our invention, reference should be had to the accompanying drawings, wherein— 95

Fig. 1 is a plan view of our complete mining machine, extended nearly to its limit, certain parts being shown in section.

Fig. 2 is a plan view of the machine fully 100 retracted.

Fig. 3 is a plan view of the carriage and bed of the machine, a portion of the latter being broken away.

Fig. 4 is a sectional front elevation of the complete machine taken approximately on the line 4—4 of Fig. 2 and viewed in the direction of the arrow. 105

Fig. 5 is an end elevation, certain parts being broken away, showing the machine 110

within the stope drift and partially extended to chip out the vein.

Fig. 6 is an end elevation showing the machine fully retracted.

Fig. 7 is a central vertical section, taken in a plane represented by the line 7—7 of Fig. 1 and viewed in the direction of the arrow, the machine being shown fully retracted and certain parts omitted for the sake of clearness.

Fig. 8 is a sectional detail taken in the direction of the arrow on the line 8—8 of Fig. 7.

Fig. 9 is a horizontal sectional detail, enlarged, of the lower set of extension cylinders, taken in the direction of the arrow on the line 9—9 of Fig. 10.

Fig. 10 is a transverse section of the same cylinders, taken in the direction of the arrow on the line 10—10 of Fig. 9.

Fig. 11 is a vertical sectional detail of one of the sets of upper extension cylinders, taken in the direction of the arrow on the line 11—11 of Fig. 12.

Fig. 12 is a transverse section of the same cylinders, taken in the direction of the arrow on the line 12—12 of Fig. 11.

Fig. 13 is a detailed front elevation of a portion of the head for carrying the percussion machines or drills.

Fig. 14 is a sectional plan, enlarged, of the hydraulic cylinders for vertically reciprocating the drill head.

Fig. 15 is a part sectional side elevation of the same, taken in the direction of the arrow on the line 15—15 of Fig. 14.

Fig. 16 is a transverse section, enlarged, of the control valve for the same, taken in the direction of the arrow on the line 16—16 of Fig. 15.

Fig. 17 is a sectional plan, of the said control valve, taken in the direction of the arrow on the lines 17—17 of Figs. 16 and 18.

Fig. 18 is a transverse section of the same, taken in the direction of the arrow on the line 18—18 of Fig. 17.

Fig. 19 is a sectional detail showing the means for mounting the percussion machines on their head, taken in the direction of the arrow on the line 19—19 of Fig. 1.

Fig. 20 is a transverse section of the drill head, taken in the direction of the arrow on the line 20—20 of Fig. 1.

Fig. 21 is a similar section taken in the direction of the arrow on the line 21—21 of Fig. 1.

Fig. 22 is a diagrammatic plan view of the entire machine, showing the fluid connections for its control and operation.

Figs. 23 and 24 are respectively a diagrammatic plan and side elevation showing the method of operating the machine in chipping out a vein of ore.

Referring now more particularly to the drawings, the reference numeral 25 designates a truck or carriage, which is supported, as shown in Figs. 4, 5, 6 and 7, by axles 26 upon which are freely rotatable wheels 27, adapted to run on rails 28 laid in the stope drift, the latter being designated, in the views in which it appears, by the letter A. The carriage is movable laterally, for a limited distance, with respect to its wheels, for the purpose of shifting the entire machine to one side or the other. To permit such movement there is provided, upon each axle 26, a removable split and hinged collar 29, shown in Figs. 5, 6, 7 and 8, which acts as a spacer between the side of the carriage 25 and the wheel 27. By removing these collars the carriage may be moved laterally, to the left as viewed in Figs. 5, 6 and 7, and the collars can then be replaced on the opposite or right-hand side of said carriage. The axles 26 slide through the wheels 27 in this movement, as shown by the dotted lines.

The carriage 25 is formed with longitudinally directed guides 30 at its sides, and in said guides is fitted, for reciprocal sliding movement longitudinally of said carriage, a bed 31, shown in Figs. 1 to 7. The means for reciprocating said bed, and the purpose for which it is done, will be hereinafter set forth. The bed 31 carries two spaced bearings 32, Figs. 1 to 6, in which are mounted the trunnions 33 of a cylinder casting 34, as shown in Figs. 1, 2, 4, 5 and 6. Said cylinder casting is therefore capable of a rocking movement about an axis parallel with the longitudinal axis of the carriage. This movement is produced by the following mechanism.

Secured to the end of each trunnion 33 is a worm wheel sector 35, Figs. 1, 2, 4 and 6, with which is meshed a worm 36 carried upon an inclined shaft 37 rotatably mounted in suitable bearings 38. The rear end of each shaft 37 carries a worm wheel 39, adapted to mesh with a worm 40 mounted on the upper end of a second inclined shaft 41. Bevel gears 42 at the lower ends of the shafts 41 mesh with corresponding bevel gears 43 secured to a longitudinally directed shaft 44 extending entirely through the bed 31. This latter shaft is provided with squared ends, upon which may be fitted cranks, one such crank being shown at 45 in Fig. 4. Thus by turning the crank 45, manually, the cylinder casting 34 may be rocked, in either direction within its bearings 32.

The cylinder casting 34 carries three parallel sets of extensible telescoping cylinders, adapted to support the percussion machines or drills, one set being positioned below and between the other two, as shown clearly in Fig. 4. This lower set comprises an outer cylinder 46, Figs. 7, 9 and 10, formed integrally with the casting 34, an inner cylinder 47, slidably in said outer cylinder, and

a piston rod 48 slidable in said inner cylinder. The outer cylinder 46 is provided with a rear head 49, Figs. 7 and 9, and the diameter of its forward portion is reduced as 5 shown at 50, to form a guide for the inner cylinder 47. Said inner cylinder carries a piston head 51, operable in the rear, or larger portion of the outer cylinder. Similarly, the interior diameter of the inner 10 cylinder is reduced at its forward portion, as shown at 52, to form a guide for the piston rod 48, and said piston rod carries a piston head 53 operable in the larger portion of said inner cylinder. Suitable packing 54 15 is provided at the forward ends of both the outer and the inner cylinders.

These cylinders are operated preferably by water under pressure. For extending the piston rod 48, water is admitted through 20 a passage 55 in the rear head 49, thus forcing both pistons 51 and 53 out. To retract said pistons, water is admitted through a port 56, Figs. 9 and 10, into the forward end of the outer cylinder, and flows thence 25 through passages 57 formed in the wall of the inner cylinder into the forward end of said inner cylinder, thus forcing both pistons 51 and 53 rearwardly. The arrows in Fig. 9 indicate the direction of flow of the 30 water and the direction of travel of the pistons during their rearward stroke.

The forward end of the piston rod 48 carries a yoke 58, Figs. 1 and 4, whose ends are fixed to and support the rear cylinders 59 35 of the two upper sets, so that said upper cylinders are moved forward and backward by said lower piston rod 48. The two upper cylinder sets are identical in construction, and are shown most clearly in Figs. 1, 11 40 and 12 wherein one set is shown in section. The cylinders 59 are guided and additionally supported by pairs of telescoping sleeves 60, Fig. 1, the rearmost of which telescope into cylindrical portions 61 of the casting 45 34. Each of the cylinders 59 is provided with a rear head 62, Figs. 1 and 11, an inner sliding cylinder 63, and a piston rod 64 50 slidable within said inner cylinder. These cylinders are similar in construction to the lower cylinders described above, there being piston heads 65 and 66 secured to the rear ends of the inner cylinder 63 and the piston rod 64 respectively. The outer end portions 55 of both cylinders form guides, as shown at 67, and are provided with suitable packing, as at 68.

The fluid connections for the upper cylinders are shown in Figs. 11 and 12. For moving the inner cylinder 63 and piston rod 64 out, the water is admitted through an aperture 69 in the rear head 62, and for retracting or moving them in, it is admitted through an aperture 70, in said head 62, and 65 passages 71 formed in the wall of the outer cylinder 59, to the interior of said cylinder

near its forward end, and thence through 70 passages 72 in the wall of the inner cylinder 63 to its interior near its forward end. The arrows in Fig. 11 indicate the direction of flow of the water and the direction of travel 75 of the pistons when retracting. It should be apparent from the foregoing that, by admitting water to the lower cylinder set, the yoke 58, carrying the upper cylinder sets, is first moved out or in, as the case may be, and that by admitting water to the upper cylinder sets, the piston rods 64 are moved still farther out or in.

The upper piston rods 64 carry, at their 80 outer ends, the head for supporting the percussion machines or drills. This head comprises a relatively stationary portion and a relatively movable portion. The relatively stationary portion consists of a transverse rectangular bar 73, Figs. 1, 2 and 7, secured 85 to the ends of the piston rods 64, and having shafts 74 formed integrally with it and extending considerably beyond the ends of said rectangular bar. The relatively movable portion comprises a bar 75 mounted for 90 limited rocking motion about the shaft portions 74, and secured thereto by bearing caps 76. The central portion of the rear face of said bar 75 is cut away, as shown at 95 77 in Figs. 7 and 21, to allow it to rock in front of the fixed bar 73.

The bar 75 is provided in its front face with a series of vertical undercut tapering slots 78, Figs. 1, 2, 13 and 19, in which are secured the correspondingly formed bases 79 of the percussion machines or drills 80. Each drill base 79 is provided with a stud and nut to lock it securely within its slot 78, as shown at 81 in Fig. 19. The percussion machines 80 may be operated by any 100 suitable form of motive power and may be of any desired form and construction adapted to receive and operate drill bits 82 for chipping away the working face B of the ore vein, but for convenience in illustration, we have represented these machines as 105 compressed air drills of the usual well known type.

The drill-head supporting bar 73 has extending from it a pair of rigid brackets 83— 115 Figs. 1, 5 and 6, whose rear ends are forked to straddle the movable drill-head 75, and whose forward ends carry horizontally disposed rollers 84 adapted to bear against the working face B of the vein, to prevent the 120 drills from being fed into said working face too rapidly by the hydraulic pressure maintained in the extension cylinders described above.

Provision is made for adjusting the 125 length of said brackets 83, as the drill bits 82 are shortened by continued wear, and sharpening, by making them in two parts held together by bolts 85 passing through slots, indicated at 86 in Fig. 1, in their for- 130

ward portions. The drill-head supporting bar 73 is also provided with rollers 87, Figs. 5 and 13, which bear against the lower face C of the working, thereby supporting the weight of the drills and drill-head when the vein has been worked out to a depth greater than the length of the drills.

The drill head 75, as stated above, is capable of oscillation about its supporting shafts 74, to enable the drills to operate throughout the width of the vein. This oscillation is carried on automatically and continuously during the operation of the machine, moving the drill bits slowly up and down across the working face. For this purpose a pair of tandem cylinders 88, Figs. 1, 2 and 5 are secured by brackets 89 to the drill-head supporting bar 73 and extend rearwardly therefrom. Said cylinders, which are shown in detail in Figs. 14 and 15, are provided with slideable pistons 90 secured to a piston rod 91, which, passing through suitable packing 92 in the heads of the cylinders, is pivotally connected at its forward end with a short arm 93 fixed to the drill-head 75, so that reciprocating movement of said pistons 90 within their cylinders causes oscillating movement of said drill-head.

The pistons 90 are preferably operated by water under pressure. It should be pointed out, in this connection, that we prefer to use two tandem cylinders merely for the purpose of securing the necessary power to oscillate the drill-head, and still keep down the diameter of said cylinders, so that they will enter the relatively narrow working, as shown in Fig. 5. The water for operating the pistons 90 is controlled by a valve, shown in Figs. 14 to 18, and said valve is preferably operated by compressed air, to secure greater speed of operation of the valve itself. The air supply is, in turn, controlled by a valve operated by the movement of the pistons.

A valve operating rod 94, Fig. 14, is secured to the rear piston 90, and extended through the head of the rear cylinder. Said rod carries two spaced collars 95, which, near the ends of the stroke, abut against and move a lever 96 whose outer end is connected with the air control valve 97. This valve, as shown in Figs. 16 and 18, is of the piston type, operating within a casing 98, and controls the air supply to a working cylinder 99, Figs. 16, 17 and 18, in which is a piston 100 mounted on the rod of the water control valve 101. In Fig. 18, 102 is the air inlet, 103 the outlets, and 104 the ports leading from the valve casing 98 to the working cylinder 99. The water control valve 101 is also of the piston type, working within a casing 105, and controls the water supply to the hydraulic cylinders 88. In Figs. 16 and 17, 106 is the water in-

let, 107 the discharge, and 108 the ports leading to the cylinders 88. Said ports communicate with passages 109, Fig. 14, which are formed partly within the cylinder walls and partly by connecting pipes 110 and which lead to the opposite ends of both hydraulic cylinders.

In order to support a portion of the weight of the drills, we provide balancing springs 111, Figs. 1, 2 and 20, extending between fixed arms 112 secured to the drill-head shafts 74 and brackets 113 secured in any suitable manner to the drills at some point sufficiently far forward of said shafts 74. The arms 112 extend through slots 114, Fig. 20 in the drill head. There may be as many of such springs as structural considerations necessitate, but for convenience only two are shown in the drawings.

As previously stated, the bed 31 is capable of reciprocating movement upon the carriage 25 in a direction parallel with the longitudinal axis of the stope drift A. This movement, like the oscillating motion of the drill head, is automatic and continuous during the operation of the machine, and carries the drill-bits back and forth horizontally over the working face B. Thus the drill-bits are continuously traveling over the working face, both vertically and horizontally, in order to enable them to reach all portions of said face. The feed guide rollers 84, being carried by the non-oscillating drill head support 73, travel over the working face only in a horizontal direction. The drill-head supporting rollers 87, also, travel back and forth over the lower face C of the working. The vertical oscillation of the drill head is clearly indicated in Figs. 5 and 24 of the drawings, and the horizontal reciprocation of the bed, and its effect on the working, is indicated diagrammatically in Fig. 23.

The aforesaid reciprocating movement of the bed 31 is produced by a pair of oppositely disposed cylinders 115, Figs. 1, 3, 4, 5, 6 and 7, mounted rigidly on the forward side of the carriage 25. Said cylinders contain slideable pistons 116, Fig. 4, fixed upon piston rods 117 whose outer ends are secured to the carriage 31 by brackets 118, as shown in Figs. 3, 4 and 7. Said cylinders are preferably operated by water under pressure, controlled by an air-operated valve 119, Figs. 3 and 6 positioned beneath the carriage 25 near one end thereof, and similar in construction and operation to the valve for controlling the hydraulic cylinders 88, described above. Said valve 119 is operated by a longitudinally disposed slideable rod 120, Figs. 3 and 4, provided with spaced collars 121 which are adapted to be engaged by the forked end of an arm 122 fixed to the bed 35 and extending downwardly therefrom through a slot 123, Fig. 3, formed in

the carriage 25. The valve 119 is connected, in the proper arrangement, with the cylinders 115 by pipes 124, Figs. 3 and 4.

The various fluid connections for controlling and operating the machine are shown diagrammatically in Fig. 22. To extend the lower cylinder set, comprising the cylinders 46 and 47 and the piston rod 48, water is admitted through a flexible connection 125, and for extending the upper cylinder sets, comprising the cylinders 59 and 63 and the piston rods 64, water is admitted through the flexible connection 126. For retracting the lower and upper cylinder sets, water is admitted through the connections 127 and 128 respectively. It is to be understood that the waste water is exhausted from all cylinders through the same connections. Suitable valves are indicated at 129 in all the said connections.

Water for operating the bed reciprocating cylinders 115 is introduced through a connection 130 to the control valve 119, to and from said cylinders by the pipes 114, and exhausted through the connection 131. Similarly, water for operating the drill oscillating cylinders 88 is introduced through a connection 132 to the control valve casing 105, and exhausted through the connection 133. Air for operating said valves is supplied through connections 134, and that for operating the drills 80 is supplied at 135.

The operation of the machine may be briefly summarized as follows. In the beginning, the cylinder sets are all fully retracted, to enable the machine to enter the stope drift A, as shown in Fig. 6. Then by means of the crank 45 shown in Fig. 4, the shaft 44 is rotated, thereby elevating or depressing the drill-head to the proper angle to enable the drills to enter and follow the vein. The machine is capable of a considerable range of elevation and depression, as shown diagrammatically in Fig. 24. The bed 31 is cut away, in its central front and rear regions, as shown at 136 in Fig. 3, to clear the lower cylinder set when the cylinder casting is swung to the limits of its movement.

When the machine has been properly set to follow the vein, water is turned into the extension cylinders through the flexible connections 125 and 126, Fig. 22, thus forcing the drill-bits 81 and their guide rollers 84 against the exposed face of the vein, as shown in Figs. 1 and 5, and at the same time air is supplied through the connection 135 for operating the drills 80. Air and water are then supplied to the valves of the reciprocating cylinders 88 and 115, through their respective connections as previously described, thus causing the drill head to oscillate up and down and the bed to reciprocate back and forth, carrying the drill-bits over every portion of the working face of the

vein. As said face is chipped away, the drill-bits are automatically fed forward by the water pressure in the extension cylinders until the limit of their extension is reached. The water is then shut off from the connections 125 and 126, Fig. 22, and turned in to the connections 127 and 128, thereby retracting the extension cylinders to the position shown in Fig. 6. At the same time, the power for operating the drills and the reciprocating mechanism is shut off. Finally, when the machine is sufficiently retracted, it is moved to a new position and the operation is repeated.

We claim:—

1. A mining machine comprising a carriage; telescoping cylinders mounted on the carriage; a piston in the innermost cylinder; a drill-head associated with said piston; and fluid-pressure connections adapted to reciprocatively extend and retract said piston and cylinders, to feed and withdraw the drill-head into and from the ore vein.

2. A mining machine comprising a carriage; telescoping cylinders mounted transversely on the carriage and adapted for extension and retraction laterally therefrom; a drill-head associated with said cylinders; and fluid-pressure connections adapted to reciprocatively extend and retract said cylinders to feed and withdraw the drill-head into and from the ore vein.

3. A mining machine comprising a carriage; telescoping cylinders mounted transversely on the carriage and adapted for extension and retraction laterally therefrom; a drill-head associated with said cylinders; fluid-pressure connections adapted to reciprocatively extend and retract said cylinders to feed and withdraw the drill-head into and from the ore vein; and fluid-pressure mechanism for angularly elevating and depressing said cylinders.

4. In a mining machine, a carriage; a plurality of sets of telescoping cylinders mounted thereon; pistons in the innermost cylinders of each set, the piston of one set being connected with the outermost cylinders of the other set; a drill-head carried by the pistons of said other sets; and fluid pressure means for extending and retracting said cylinders and pistons.

5. In a mining machine, a carriage; a series of telescoping cylinders, the outermost cylinder being mounted upon said carriage; a piston within the innermost cylinder; a second series of telescoping cylinders, the outermost cylinder thereof being connected with and moved by the piston of the first series of cylinders; a piston within the innermost cylinder of said second series; a drill-head carried by said second piston; and fluid pressure means for operating said cylinders and pistons.

6. In a mining machine, a carriage; a cyl-

- inder casting mounted thereon; a series of telescoping cylinders, the outermost cylinder thereof being formed integrally with said casting; a piston within the innermost cylinder; a second series of telescoping cylinders, the outermost cylinder thereof being connected with and moved by the piston of the first series of cylinders; a series of telescoping guide sleeves surrounding the outermost cylinder of said second series; said sleeves operating within a cylindrical bore formed in said casting; a piston within the innermost cylinder of the second series; a drill-head carried by said second piston; and fluid pressure means for operating said cylinders and pistons.
7. In a mining machine, a carriage; a drill-head; means for supporting said drill-head from said carriage; mechanism for oscillating said drill-head in a vertical plane; and mechanism for reciprocating said supporting means upon said carriage in a horizontal plane perpendicular to the plane of oscillation of said drill-head.
8. A mining machine comprising a carriage; a series of telescoping cylinders, the outermost cylinder being mounted upon said carriage; a piston within the innermost cylinder; a second series of telescoping cylinders, the outermost cylinder thereof being connected with and moved by the piston of the first series of cylinders; a piston within the innermost cylinder of said second series; a drill-head carried by said second piston and connected therewith for oscillatory movement; fluid pressure means for oscillating said drill-head; and fluid pressure means for reciprocating said cylinders and pistons in a plane perpendicular to the plane of oscillation of the drill-head.
9. A mining machine comprising a carriage; a series of telescoping cylinders, the outermost cylinder being mounted upon said carriage; a piston within the innermost cylinder; a second series of telescoping cylinders, the outermost cylinder thereof being connected with and moved by the piston of the first series of cylinders; a piston within the innermost cylinder of said second series; a drill-head carried by said second piston and connected therewith for oscillatory movement; fluid pressure means for oscillating said drill-head; fluid pressure means for reciprocating said cylinders and pistons in a plane perpendicular to the plane of oscillation of the drill-head; and fluid pressure means for angularly elevating and depressing said cylinders and pistons.
10. A mining machine comprising a carriage; a series of telescoping cylinders mounted transversely upon said carriage; a piston within the innermost cylinder of the second series; a second series of telescoping cylinders parallel with the first series, the outermost cylinder of said second series being connected with and moved by the piston of the first series; a piston within the innermost cylinder of said second series; a drill-head carried by said second piston and connected therewith for oscillatory movement; fluid pressure means for oscillating said drill-head; and fluid pressure means for reciprocating said cylinders and pistons in a plane perpendicular to the plane of oscillation of the drill-head.
11. A mining machine comprising a carriage; a series of telescoping cylinders mounted transversely upon said carriage; a piston within the innermost cylinder of said series; a second series of telescoping cylinders parallel with the first series, the outermost cylinder of said second series being connected with and moved by the piston of the first series; a piston within the innermost cylinder of said second series; a drill-head carried by said second piston and connected therewith for oscillatory movement; fluid pressure means for oscillating said drill-head; and fluid pressure means for reciprocating said cylinders and pistons in a plane perpendicular to the plane of oscillation of the drill-head.
12. In a mining machine, a carriage; an oscillatory drill-head; means for supporting said drill-head from said carriage; an hydraulic cylinder carried by said supporting means; a piston within said cylinder, said piston being connected with said drill-head for causing oscillation of the latter upon its supporting means; a valve for controlling the admission and discharge of water to and from said cylinder; and pneumatic devices for operating said valve; said pneumatic devices being automatically controlled by the movement of said piston.
13. In a mining machine, a carriage; a bed mounted thereon for reciprocative movement; a drill-head supported from said bed; an hydraulic cylinder mounted on said carriage; a piston operable within said cylinder and connected with said bed; a valve for controlling the admission and discharge of water to and from said cylinder; and pneumatic devices for operating said valve; said pneumatic devices being automatically controlled by the movement of said bed.

In testimony whereof we have signed our names to this specification.

GEORGE W. STARR.
WILLIAM D. PAYNTER.
